UNITED STATES PATENT OFFICE.

RUDOLPH JACOB GOEPPINGER, OF ST. FRANCIS, ARKANSAS.

SURVEYOR'S COMPASS.

SPECIFICATION forming part of Letters Patent No. 633,832, dated September 26, 1899.

Application filed March 21, 1898. Serial No. 674,642. (No model.)

To all whom it may concern:

Be it known that I, RUDOLPH JACOB GOEPPINGER, of St. Francis, in the county of Clay and State of Arkansas, have invented a new and Improved Surveyor's Compass, of which the following is a full, clear, and exact description.

The object of the invention is to provide a new and improved surveyor's compass arranged to confine the vibrations and oscillations of the needle to cause the latter to come to a state of rest in a comparatively short time, thus enabling a surveyor to run lines quickly.

15 The invention consists of novel features and parts and combinations of the same, as will be described hereinafter, and pointed out in the claims.

Reference is to be had to the accompanying drawings, forming a part of this specification, in which similar characters of reference indicate corresponding parts in all the figures.

Figure 1 is a plan view of the improvement. Figure 2 is a sectional side elevation of the same on the line 2 2 of Fig. 1. Fig. 3 is a transverse section of the same on the line 3 3 of Fig. 1. Fig. 4 is a plan view of part of the needle-lifting device. Fig. 5 is a perspective view of the spring for holding the slide for the needle-lifting device in position. Fig. 6 is a perspective view of the holder for the spring. Fig. 7 is a side elevation of the slide for the needle-lifting device. Fig. 8 is an end elevation of the same. Fig. 9 is a plan view of a modified form of the improvement. Fig. 10 is a transverse section of the same on the line 10 10 of Fig. 9. Fig. 11 is a plan view of another modified form of the improvement. Fig. 12 is a plan view of another modified form of the improvement. Fig. 13 is a transverse section of the same on the line 13 13 of Fig. 12, and Fig. 14 is an inverted plan view of the same.

The surveyor's compass illustrated in Figs. 1 to 8, inclusive, is provided with the usual casing A, supporting the pivot B, on which the cap C' of the needle C is mounted to turn, the needle being arranged under a glass D and adapted to indicate on the usual graduation E. In order to limit the vibrations or oscillations of the needle C to bring the needle to a state of rest in a comparatively short

time, a needle-retaining device F is provided, arranged to engage the needle and limit the oscillations thereof, and, as shown in Fig. 1, 55 said device is arranged at one end of the needle with arms at each side thereof. It will be understood that the needle remains permanently between the arms of the retaining device.

As illustrated in Fig. 1, the retaining device F is made in the form of a U-shaped bar having its ends fastened to a ring G, mounted to turn on a bearing H, secured to the bottom of the casing A and concentric with the pivot B. The peripheral surface of the ring G is provided with teeth in mesh with a pinion I, secured on a shaft I', mounted to turn in the bottom of the casing, the lower end of the shaft being provided with a knob I² for 70 conveniently turning the shaft and the pinion to turn the ring G in its bearings H, so as to bring the retaining device F to the proper position for limiting the final oscillations of the needle C. Thus when the compass is placed in position the surveyor or other person can readily move the retaining device F into a position approximately corresponding to the final position of the needle, so that the needle C has its oscillations limited between the side arms of the retaining device, and consequently comes to a state of 75 rest in a very short time between the side arms of the retaining device.

As shown, for instance, in Fig. 1, the needle points to seventy degrees, and the retaining device F has its side arms extending a few degrees above and below the seventy degrees mentioned. Thus the retaining device does not interfere in any way with the proper 90 pointing of the needle, so that the latter is free to oscillate between the side arms of the retaining device; but the oscillations are limited, so that the needle will come to a state of rest in a very short time.

I do not limit myself to the particular construction of the needle-retaining device F or to the particular mode of revolving the retaining device or devices to control the needle at any desired point on the compass, as it is evident that the form thereof may be greatly varied without deviating from the spirit of my invention. For instance, as shown in Fig. 9, the needle-retaining device F con-

sists of two pins F' , placed a short distance apart and between which extends one end of a needle C^2 . The pins F' are secured on a movable ring G' , mounted to turn in bearings H' , carried by a casing A' similar to the casing A and having the usual glass D' and the graduation E' for the needle to indicate on.

As illustrated in Fig. 11, the retaining device consists of two pins F^2 F^3 , arranged diametrically opposite each other for engaging opposite sides of the ends of the needle C^3 . The pins F^2 F^3 are secured on a movable ring G^3 , similar to the ring G' , and under the control of the operator by means of a pinion I^4 , similar to the pinion I^3 , used for turning the ring G' .

In connection with the needle-retaining device I provide a needle-lifting device controlled by the ring G , as illustrated in the drawings. The needle-lifting arm J is secured on a stirrup G^8 , carried by the ring G , the free end of the lifting-arm extending under the cap C' of the needle C , so that when the arm J is swung upward the cap C' is lifted off the pivot B and pressed with its top surface against the under side of the glass D to lock the needle in place. The lifting-arm J is adapted to travel up an inclined projection or arm K , carried by a slide L , fitted to slide on the bearing H , but held normally in position thereon by a spring N , pressing against the inside of the bearing and carried by a holder N' , removably held on the inner side of the slide L . The latter extends with its outer edge into a slot or groove G^4 , formed on the ring, so that when the latter is turned either end of the slot is moved in contact with the slide and carries the same along on the bearing H .

When the several parts are in the position shown in Fig. 1 and it is desired to actuate the lifting-arm J and move the needle-cap C' off its pivot B , then the operator turns the knob I^2 to turn the ring G in the direction of the arrow a' and move the lifting-arm J up on the projection K , so as to swing the lifting-arm J upward and move the cap C' in a like direction, thus locking the needle. When it is desired to again free the needle, the ring G is turned in the direction opposite to the arrow a' and the arm J slides off the projection K and swings downward to permit the cap C' to again seat itself on its pivot B . Normally the lifting-arm J is out of engagement with the projection K and the slide L moves with the lifting-arm J when the ring G is turned in the inverse direction of the arrow a' to bring the retaining device F in proper position to limit the oscillations of the needle, as previously explained.

The device is very simple and durable in construction, and the arrangement shown in Figs. 9, 10, and 11, for instance, can be readily applied to any ordinary compass, it being understood that in this case the lifting device for the needle is of the usual construction.

In the modified form shown in Figs. 12, 13,

and 14 the casing A^2 is made in two principal sections A^3 and A^4 , of which the section A^4 is mounted to turn on the other section A^3 to bring the graduation into the proper position relative to the needle C^4 , the swinging or vibration thereof being limited by a retaining device consisting of two pins F^4 F^5 , arranged similar to the pins F^2 and F^3 —that is, diametrically opposite each other—for engaging opposite sides of the ends of the needle C^4 .

The pins F^4 and F^5 are formed on clamping-screws F^6 and F^7 , respectively, screwing in a ring A^5 , secured to and forming part of the fixed casing-section A^8 , and on which the other section is mounted to turn, the screws carrying a clamping-ring A^6 for locking the sections together on screwing up the screws F^6 and F^7 .

The needle-lifting device shown in Figs. 12 and 13 consists of a lifting-arm J' , pivoted at its outer end at J^2 on the ring A^5 and having its inner forked end under the needle-cap, a screw J^3 serving to swing the arm up to lift the needle off its pivot B^2 . Said screw passes vertically through the casing from below and engages the arm J' with its point. The screw is indicated in dotted lines in Fig. 12.

It will be understood that in each of the constructions described I provide a retaining device or stop projecting into the path of the needle, said stop being movable about the center of the compass relatively to the casing or card carrying the graduation, so that the stop can be brought into any position relatively to the graduation.

Having thus described my invention, I claim as new and desire to secure by Letters Patent—

1. A compass, comprising a casing having a graduation, a needle arranged to indicate thereon, and a retaining device or stop projecting into the path of the needle and movably mounted on the casing so that it may be brought in registry with different points of the graduation.

2. A compass, comprising a casing having a graduation, a needle arranged to indicate thereon, and a retaining device or stop projecting into the path of the needle and mounted to turn relatively to the casing about the axis of the needle.

3. A compass, comprising a casing having a graduation, a needle arranged to indicate thereon, a ring mounted to turn on the casing, and a retaining device or stop projecting from said ring into the path of the needle.

4. A compass, comprising a casing having a graduation, a needle arranged to indicate thereon, a retaining device or stop projecting into the path of the needle and movably mounted on the casing so as to be capable of being shifted into registry with different points of the graduation, and a needle-lifter controlled by the movement of said retaining device.

5. A compass provided with a retaining device for the needle, comprising a ring mov-

able in bearings on the compass-casing, retainers on the ring and in the path of the oscillating needle, and means for turning the said ring to bring the retainers into the desired position relative to the needle, substantially as shown and described.

6. A compass provided with a needle-lifter, comprising a movable ring, a needle-lifting arm carried by the ring, a slide adapted to be

moved by the ring, but normally stationary, and a projection on the slide and adapted to be engaged by the said lifting-arm on moving the ring, substantially as shown and described.

RUDOLPH JACOB GOEPPINGER.
